UNITED STATES PATENT OFFICE.

GEORGE S. CHILES, OF CHICAGO, ILLINOIS, ASSIGNOR TO DALMAN, CHILES COMPANY,
A CORPORATION OF DELAWARE.

RAILWAY TRUCK.

Application filed January 12, 1923. Serial No. 612,309.

To all whom it may concern:

Be it known that I, GEORGE S. CHILES, a citizen of the United States, and a resident of Chicago, in the county of Cook and State of Illinois, have invented certain new and useful Improvements in Railway Trucks, of which the following is a specification.

The object of my invention is to provide an improved form of roller bearing to permit limited endwise movement of the truck bolster relative to the side frames. Rollers have been used in this connection to a considerable extent in the past. In the usual construction the rollers rest in concave seats provided in the under surface of the bolster and upon the upper surface of a spring cap, the upward travel of the rollers upon these concave surfaces acting to restrain the side sway of the car body. My improvement is an improved application of such rollers, some features of which are particularly adapted to use in connection with the improved truck shown in my prior application, Serial No. 611,387, filed January 8th, 1923, now Patent #1,457,345 granted June 5, 1923, and other features of more general application.

In the drawings,

Figure 1 is a side view partly in section and partly in elevation of the end of a truck embodying my invention,

Figure 2 is a section on line 2, 2 of Figure 1, and

Figure 3 is a vertical section at the center of Figure 1.

The side frame shown in Figure 1 is of a form described in my co-pending application above referred to. This side frame comprises in an integral structure compression member 4, tension member 5, and columns 6. Integrally formed with the tension member is a spring seat having a central section 7 at a lower level than the end sections 8 and connected thereto by the integral vertically extending parts 9. At the end of each of the elevated end sections 8, the web of which it is formed is deflected upwardly, as shown at 10, and forms the web of the column. In the structure illustrated, the spring assemblage consists of six springs, a group of four intermediate springs seated upon the depressed central section of the spring seat, and a single end

spring upon each of the elevated end sections. The springs are shown as all of the same length, the tops of the end springs 11 being upon a higher level than the tops of the intermediate springs 12. Overlying the springs is a spring cap, designated generally by the numeral 13. This spring cap is provided upon its under surface with a spring seat having its central section 16 at a lower level than the end sections 17, and is provided upon its upper side with central and end roller bearing sections 14 and 15, respectively. The bolster, designated generally by the numeral 18, is provided with a relatively deep central section 19 and the shallower side sections 20. The deep central section 19 of the bolster is provided upon its under surface with the central roller bearing section 21 and upon the under side of the shallower extensions 20 with the end roller bearing sections 22. These roller bearings take the form of arcs 23 which form concave seats for the central rollers 24. Similar concave seats 25 are provided for the end rollers 26. To restrain the rollers against endwise movement the concave seats are provided with end walls 27. The spring cap 13 is provided with column wear lugs 28 which have a close working fit between the column guides 29 upon the webs 10 of the columns. This has the effect of restraining the spring cap against movement transversely of the side frame. The bolster is provided with wear lugs 30 which are sufficiently narrower than the space between the guide lugs 29 to permit endwise movement of the bolster upon the roller bearings above described, the endwise movement of the bolster being limited by contact of the sides of the guide lug 30 with the inner faces of the guide lugs 29.

I claim as my invention:

1. In a railway truck, a side-frame, a bolster, rollers interposed between said side-frame and bolster, said bolster being provided with surfaces at different levels bearing upon said rollers.
2. In a railway truck, a side-frame, springs supported on said side-frame, a spring cap supported on said springs, a bolster, the upper side of said spring cap and lower side of the ends of said bolster being provided with central and end roller bearing surfaces,

8. A railway car truck comprising a side frame having spaced bolster columns, a central depressed channel-shaped base portion therebetween with elevated shelf portions at each side thereof, a connecting member of channel shape resting on said depressed portion, a plate having a depressed central portion disposed in said depressed portion of said frame and raised side portions resting on said shelf portions, a plurality of springs supported on the central depressed portion of said plate, and additional springs supported on the raised ends of said plate, and a roller seat resting on and supported by all of said springs. 70 75
9. In a railway truck, a side frame, a spring seat on said side frame having end sections elevated above the central section thereof, a spring cap having on its under side a spring seat having end sections elevated above the central section thereof and having upon its upper side end and central roller bearing seats, said end roller bearing seats being at a higher level than said central roller bearing seat, a bolster having an end bearing relatively deep at its central part and relatively shallow at the sides, said central part of said end bearing lying over said central roller bearing seat and said relatively shallow sides of said end bearing overlying said end roller bearing seats, springs between said spring seat and spring cap and rollers between said cap and bolster. 85 90 95 100
10. In a car truck, a side-frame, a bolster having a centrally disposed roller bearing surface on its underside, an assemblage of springs supported on the lower part of said side-frame, said assemblage of springs being of substantially greater width than and extending beyond said roller bearing surface, a single spring cap overlying and resting upon said entire assemblage of springs, and rollers of substantially the length of the roller bearing surface on the underside of said bolster, said spring cap providing a seat for said rollers. 105 110 115
11. In a car truck, a side-frame, a bolster having a relatively deep central section and shallower side sections with a roller bearing surface on the underside of said central section, an assemblage of springs supported on the lower part of said side-frame, said assemblage of springs being of substantially greater width than and extending beyond the central section of said bolster, a single spring cap overlying and resting upon said entire assemblage of springs, and rollers of substantially the length of the roller bearing surface on the underside of said central section of the bolster, said spring cap providing a seat for said rollers. 120 125 128
- said end roller bearing surfaces being elevated above said central roller bearing surfaces, and rollers lying transversely of said bolster and between said bearing surfaces on said bolster and spring cap. 15
3. In a railway truck, side frames each having a compression member, a tension member and columns, a bolster having its ends between said columns, springs supported at different levels on said tension member between said columns, a spring cap between said columns and resting on said springs, and rollers between said spring cap and bolster. 20
4. In a railway truck, side frames each having a compression member, a tension member and columns, a bolster having its ends between said columns, springs supported at different levels on said tension member between said columns, a spring cap between said columns and resting on said springs and having on its under side spring bearing surfaces at different levels, and rollers between said spring cap and bolster. 25
5. A railway car truck of the arch bar type comprising a side frame having spaced bolster columns of channel shape in cross section with said channels facing each other, a roller seat extending between said columns having end portions substantially fitting in said channels and vertically movable therein, rollers carried on said seat, and a bolster supported on said rollers having lateral projections disposed in said channels of said columns and vertically movable therein, said projections being of less width than the width of said channel whereby longitudinal movement of the bolster transversely of the side frame is permitted. 30 35 40
6. A railway car truck comprising a side frame having spaced bolster columns, a roller seat disposed and movable vertically between said columns, a plurality of springs supporting said seat from the side frame, additional springs at the ends of said seat also supporting the same from the side frame, said additional springs being supported at a different level in said side frame, said seat having a central depressed portion resting on said plurality of springs, the end portions at a higher level resting on said additional springs, and a bolster extending over the ends of said seat and movable vertically in said columns and also being adapted for endwise movement therein transversely of said side frame. 45 50 55 60
7. A railway car truck comprising a side frame having spaced bolster columns and a central depressed channel-shaped base portion therebetween with elevated shelf portions at each side thereof, a roller seat having a central depressed channel shaped portion and raised end portions, a plurality of springs supported in the depressed portion of said side frames and supporting the de-

12. In a car truck, a side frame, a bolster having a centrally disposed roller bearing surface on its underside, an assemblage of springs supported on the lower part of said side frame, said assemblage of springs being of substantially greater width than and extending beyond said roller bearing surface and comprising single end springs and intermediate springs offset horizontally from the straight line joining the centers of said end springs, 10 from the straight line joining the centers of said end springs, a single spring cap overlying and resting upon said entire assemblage of springs, and rollers of substantially the length of said roller bearing surface 15 on the underside of said bolster, said spring cap providing a seat for said rollers.
13. In a car truck, a side frame, a bolster having a relatively deep central section and shallower side sections with a roller bearing surface on the underside of said central section, an assemblage of springs supported on the lower part of said side-frame, said assemblage of springs being of substantially greater width than and extending beyond 20 the central section of said bolster and comprising single end springs and intermediate springs offset horizontally from the straight line joining the centers of said end springs, a spring cap overlying and resting upon said 25 entire assemblage of springs, and rollers of substantially the length of the roller bearing surface on the underside of said central section of the bolster, said spring cap providing a seat for said rollers.
- 30 14. In a car truck, a side-frame comprising upper and lower members and columns, a bolster having a roller bearing surface on its underside, an assemblage of springs supported on the lower member of said side-frame, said assemblage of springs comprising single end springs and intermediate springs offset horizontally from the straight line joining the centers of said end springs, 35 a spring cap overlying and resting upon said entire assemblage of springs, rollers interposed between said bearing surface and said spring cap, each of said columns having guide flanges projecting toward the opposite column, and the ends of said spring cap being received between the guide flanges on 40 said columns.
15. In a car truck, a side-frame comprising upper and lower members and columns, a bolster having a roller bearing surface on its underside, an assemblage of springs supported on the lower member of said side-frame, said assemblage of springs comprising single end springs and intermediate springs offset horizontally from the straight line joining the centers of said end springs, 45 a spring cap overlying and resting upon said entire assemblage of springs, and rollers interposed between said bearing surface and said spring cap, each of said columns having guide flanges projecting toward the opposite column, and the ends of said spring cap being received between the guide flanges on 50 said columns.
- 55 16. In a car truck, a side-frame comprising upper and lower members and columns, a bolster having a roller bearing surface on its underside, an assemblage of springs supported on the lower member of said side-frame, said assemblage of springs comprising single end springs and intermediate springs offset horizontally from the straight line joining the centers of said end springs, 60 a spring cap overlying and resting upon said entire assemblage of springs, and rollers interposed between said bearing surface and said spring cap, said columns presenting vertical guide channels adapted to be engaged by the ends of said spring cap.
- 65 In witness whereof, I hereunto subscribe my name this 10th day of January, A. D., 1923.

GEORGE S. CHILES.
